INCINERATOR

Richard Goder, Chicago, Ill.

Application June 29, 1942, Serial No. 448,883

22 Claims. (Cl. 110—8)

The present invention relates to incinerators and more particularly to means for preheating the material to be incinerated and to means for preheating the supporter of combustion.

Among the objects of the invention is to provide a novel incinerator structure having a furnace part for the burning of fuel or the material incinerated or both, combined with means for preheating the material to be incinerated, and to preheat from the waste gases of combustion the air for supporting combustion of the material, with or without means for supplying heated supporter of combustion to the preheated material being incinerated as a priming of combustion thereof.

Other objects, advantages, capabilities, features, and the like are comprehended by the invention as will later appear and as are inherently possessed by the invention.

Referring to the drawings:

Fig. 1 is a transverse and vertical sectional view of the invention taken in planes represented by line 1—1 in Fig. 2 of the drawings;

Fig. 2 is a horizontal sectional view taken in a plane represented by line 2—2 in Fig. 1 of the drawings;

Fig. 3 is a fragmentary sectional view taken in planes represented by line 3—3 in Fig. 1 of the drawings;

Fig. 4 is a fragmentary section view taken in planes represented by line 4—4 in Fig. 1 of the drawings; and,

Fig. 5 is a fragmentary vertical and transverse sectional view similar to Fig. 1 of an alternative form of device.

Referring more in detail to the drawings, the embodiments selected to illustrate the invention are shown in the form of a furnace comprising a base structure 1, a rear wall structure 2, a front wall structure 3, a suitable top wall structure 4, side wall structures 5 and 6 with intermediate wall structures 7 and 8 providing between them chambers 9 and 10, of which the chambers 10 constitute combustion chambers.

The products of combustion pass from the outer to the inner chambers 10 by way of a port or door 11 provided in the wall 7 between the chambers 10, and thence with the products of combustion of the inner chamber 10 by way of the port or door 12 into chamber 9, thence by way of ports or doors 13, 14 and 15 respectively in walls 8, 7 and 6, to flow out by way of a flue 16 leading to a suitable stack (not shown).

At the rear of each chamber 10 is a preheating chamber 17 through which the hot gases flow

when passing out through the ports 13, 14 and 15 to the flue 16. At the front are suitable stoking doors 18 and cleanout door 19 for chamber 9.

In each combustion chamber 10 (see Fig. 1) is a suitable grate 20 over an ash pit 21 and located between air inlet ducts 22 having heated air inlets 23 communicating with a heated air box 24, and outlets 25 leading to the ash pits 21 and controlled by suitable damper-valves 26. At the rear of the grate 20 is a tuyère construction 27 which is inclined and is provided with ducts having at their lower ends outlets 28, and having their upper ends supported on suitable arches 29 in the chambers 17.

Leading into the upper ends of the tuyères 27 are heated air ducts 30 supported at the forward ends in the rear end of the tuyères and at the rear ends in the portion 31 of the rear wall 2, these ducts 30 having communication with an air chamber or box 32 having an inlet 33 from any suitable blower or the like (not shown).

The upper surfaces of the tuyères in the aggregate form an inclined wall 34 over which the material to be incinerated slides toward the fire on the grate 20. Such wall 34 preferably is provided with apertures 35 and 36 for passage of some of the heated air from the tuyères 27 to assist in the combustion or incinerating of the material sliding down over the surface or wall 34.

The tuyères 27 and the ducts 30 are so exposed to the hot gases passing through the chamber 17 as to absorb heat therefrom and to heat the air passing through the ducts 30 and the tuyères 27. Likewise some of the heat of the hot gases in the chamber 17 passes through the wall 31 of the air box 24 to also heat the air passing through the air box 24 to the ducts 22.

At the top of each chamber 17 is a metal cover or platform 38 to form a closure for the chamber 17 and to receive and heat the waste material to be incinerated. The hot gases passing through the chamber 17 heat the platform 38 so as to preheat such material. The material is charged onto the platform 38 by way of a chute 39 above the platform.

For the purpose of regulably feeding the material piled up on the platform 38 any suitable means may be used, such as a feed screw 40 as shown in Fig. 1, or a pusher 41 as shown in Fig. 5, or any other suitable means. The feed screw 40 is rotatably supported by way of a shaft 42 rotatable in suitable bearing means 43 carried by the frame 44 set in the wall 2, and is operated by any suitable power source (not shown).

In Fig. 5 the pusher 41 reciprocates in a collar

45 set in the wall 2 and by way of a track means 46 riding on rollers 47 carried on supports 48 on the base of the collar 45 and a top 49 of a frame structure 50 at the rear of the wall 2. Operation of the pusher is effected by means of a link 51 articulated to a lug 52 secured to the pusher 41 and pivotally connected to a crank 53 operatively connected to a wheel 54 driven by a belt 55 in turn driven by a suitable motor 56 mounted on a pedestal 57.

Referring to Fig. 4, it will be noted that the ducts 22 have inclined walls 58 for preventing the piling up of material on the top of the duct 22 and to guide the material down to the grate 20.

In use the material to be incinerated is charged down through the chute 39 onto the platform 38. This platform is heated by waste gases as above described so that the material is preheated. The material is then gradually fed by means of the feed screw 40 or the pusher 41 to move down over the inclined wall 34 of the tuyères, and thence onto the grate 20. The fire on the grate 20 will consume some of the material as it moves down the wall 34 and onto the grate 20.

The products of combustion pass through the ports or doors in the side walls of the combustion chambers and proceed into the chamber 9. From this latter chamber the hot gases pass through the chamber 17 and preheat the tubes 30, the tuyères 27, as well as the air box 31. This heat hits the air passing through the air tubes 30 and the tuyères 27. The air is introduced by way of the inlets 33 and the air boxes 32. From the air box 24 the heated air passes through the ducts 22 and thence by way of the ports 25 into the ash pits 21 beneath the grates 20. Thus heated air supports combustion on the grates. By reason of the platform 38 being heated the material to be incinerated is thus preheated so that further incinerating of the material moving down over the wall 34 is enhanced. To assist the combustion of the material on the wall 34 the apertures 35 and 36 provide a means for the introduction of the heated air into the mass on the wall 34 so as to effect what might be called a prime combustion or burning of the material.

While I have herein described and upon the drawings shown a few embodiments of the invention, it is to be understood that the invention is not limited thereto but comprehends other constructions, arrangements of parts, details, and features, without departing from the spirit of the invention.

Having thus disclosed the invention, I claim:

1. In an incinerator having a combustion chamber with grate means for the burning of material thereon, comprising in combination therewith a preheating chamber rearwardly of and adjacent to the combustion chamber for passage therethrough of hot gases, and a tuyère construction between and common to said chambers and having an inclined wall extending to the grate means and provided with a duct for the passage of air to support combustion and leading to the grate means, said preheating chamber being adjacent to said duct for heating said duct to preheat said air passing therethrough.

2. In an incinerator having a combustion chamber with grate means for the burning of material thereon, comprising in combination therewith a preheating chamber rearwardly of and adjacent to the combustion chamber for passage therethrough of hot gases, and a tuyère construction between and common to said chambers and having an inclined wall extending to the grate means

and provided with a duct for the passage of air to support combustion, an air chamber for receiving the air from said duct, said preheating chamber being adjacent to said duct and said air chamber being adjacent to said duct and said air for preheating said air passing therethrough, and a passage communicating with said air chamber for conducting the heated air to said grate means.

10. 3. In an incinerator having a combustion chamber with grate means for the burning of material thereon, comprising in combination therewith a preheating chamber rearwardly of and adjacent to the combustion chamber for passage therethrough of hot gases, and a tuyère construction between and common to said chambers and having an inclined wall extending to the grate means and provided with a duct for the passage of air to support combustion, an air chamber beneath said duct for receiving the air from said duct, said preheating chamber being rearwardly of said duct and said air chamber for heating said duct and air chamber for preheating said air passing therethrough, means connected to said air chamber for conducting the heated air therefrom to said grate means, and valve means in said conducting means for regulating the conduction of said air to said grate means.

4. In an incinerator having a combustion chamber with grate means for the burning of material thereon, comprising in combination therewith a preheating chamber rearwardly of and adjacent to the combustion chamber for passage therethrough of hot gases, and a tuyère construction between and common to said chambers and having an inclined wall extending to the grate means and provided with a duct for the passage of air to support combustion, a platform adjacent said tuyère construction for holding material to be incinerated, means for feeding said material from said platform to the inclined wall of the tuyère construction, said preheating chamber being located beneath said platform for heating said platform for preheating said material, and a passage communicating with said tuyère construction and said grate means for conducting the air from said duct to said grate means.

5. In an incinerator having a combustion chamber with grate means for the burning of material thereon, comprising in combination therewith a preheating chamber rearwardly of and adjacent to the combustion chamber for passage therethrough of hot gases, and a tuyère construction between and common to said chambers and having an inclined wall extending to the grate means and provided with a duct for the passage of air to support combustion, a platform adjacent said tuyère construction for holding material to be incinerated, means for feeding said material from said platform to the inclined wall of the tuyère construction, said platform being located between said preheating chamber and the combustion chamber for heating both sides of said platform for preheating said material, and a passage communicating with said duct for conducting the air from said duct to said grate means, said duct extending through said preheating chamber for heating said duct on all sides thereof to preheat said air passing therethrough.

6. In an incinerator having a combustion chamber with grate means for the burning of material thereon, comprising in combination therewith a preheating chamber rearwardly of and adjacent to the combustion chamber for passage therethrough of hot gases, and a tuyère construction

between and common to said chambers and having an inclined wall extending to the grate means and provided with a duct for the passage of air to support combustion, an air supply chamber, air ducts connected to said air supply chamber and to said tuyère construction and extending through said preheating chamber for heating said air ducts to preheat the air flowing therethrough and to said tuyère structure, and means for conducting the heated air from said tuyère construction to said grate means.

7. In an incinerator having a combustion chamber with grate means for the burning of material thereon, comprising in combination therewith a preheating chamber rearwardly of and adjacent to the combustion chamber for passage therethrough of hot gases, and a tuyère construction between and common to said chambers and having an inclined wall extending to the grate means and provided with a duct for the passage of air to support combustion, an air supply chamber, air ducts connected to said air supply chamber and to said tuyère construction and extending through said preheating chamber for heating said air ducts to preheat the air flowing therethrough and to said tuyère structure, a platform adjacent said tuyère construction for holding material to be incinerated and being located between said preheating chamber and the combustion chamber to be heated from both sides thereof to preheat said material, and means for conducting the heated air from said tuyère construction to said grate means.

8. An incinerator having a combustion chamber with grate means for the burning of material thereon, comprising a tuyère construction having an inclined surface extending to the grate means and provided with a duct for the passage of air to support combustion, said combustion chamber being located at one side of said grate means and said tuyère construction, a preheating chamber located at the other side of said tuyère construction and separated from said combustion chamber by said tuyère construction, a passage between said chambers for conducting the hot products of combustion from said combustion chamber to said preheating chamber to heat said tuyère construction and to preheat the air passing through said tuyère construction, and means for conducting the heated air from said tuyère duct to said grate means.

9. An incinerator having a combustion chamber with grate means for the burning of material thereon, comprising a tuyère construction having an inclined surface extending to the grate means and provided with a duct for the passage of air to support combustion, said combustion chamber being located at one side of said grate means and said tuyère construction, a preheating chamber located at the other side of said tuyère construction and separated from said combustion chamber by said tuyère construction, a passage between said chambers for conducting the hot products of combustion from said combustion chamber to said preheating chamber to heat said tuyère construction from underneath and to preheat the air passing through said tuyère construction, passage means for conducting the heated air from said tuyère duct to said grate means, said latter air conducting means comprising a duct extending along the grate means from said tuyère construction to below said grate means to be heated by the products of combustion in

the combustion chamber and to supply heated air for supporting combustion on said grate means.

10. An incinerator having a combustion chamber with grate means for the burning of material thereon, comprising a tuyère construction having an inclined surface extending to the grate means and provided with a duct for the passage of air to support combustion, said combustion chamber being located at one side of said grate means and said tuyère construction, a preheating chamber located at the other side of said tuyère construction and with the latter located between said combustion chamber and said preheating chamber, a passage between said chambers for conducting the hot products of combustion from said combustion chamber to said preheating chamber to heat said tuyère construction and to preheat the air passing through said tuyère construction, an air chamber located adjacent to said preheating chamber for receiving heat from the hot gases in the preheating chamber and for receiving the air from said tuyère duct to heat the air in said air chamber, an ash pit chamber beneath said grate means, and means for conducting the heated air from said air chamber to said ash pit chamber.

11. An incinerator having a combustion chamber with grate means for the burning of material thereon, comprising a tuyère construction having an inclined surface extending to the grate means and provided with a duct for the passage of air to support combustion, said combustion chamber being located at one side of said grate means and said tuyère construction, a preheating chamber located at the other side of said tuyère construction and with the latter located between said combustion chamber and said preheating chamber, a passage between said chambers for conducting the hot products of combustion from said combustion chamber to said preheating chamber to heat said tuyère construction and to preheat the air passing through said tuyère construction, an air chamber located adjacent to said preheating chamber for receiving heat from the hot gases in the preheating chamber and for receiving the air from said tuyère duct to heat the air in said air chamber, an ash pit chamber beneath said grate means, and means for conducting the heated air from said air chamber to said ash pit chamber.

12. An incinerator having a combustion chamber with grate means for the burning of material thereon, comprising a tuyère construction having an inclined surface extending to the grate means and provided with a duct for the passage of air to support combustion, said combustion chamber being located at one side of said grate means and said tuyère construction, a preheating chamber located at the other side of said tuyère construction and with the latter located between said combustion chamber and said preheating chamber, a passage between said chambers for conducting the hot products of combustion from said combustion chamber to said preheating chamber to heat said tuyère construction and to preheat the air passing through said tuyère construction, an air chamber located adjacent to said preheating chamber for receiving heat from the hot gases in the preheating chamber and for receiving the air from said tuyère duct to heat the

air in said air chamber, an ash pit chamber beneath said grate means, and means for conducting the heated air from said air chamber to said ash pit chamber, said latter air conducting means comprising a duct extending along the grate means to be heated by the products of combustion from said grate means, an air supply chamber, air ducts connected to said air supply chamber and to said tuyère construction, means for heating said air ducts to preheat the air flowing therethrough and to said tuyère structure, and a platform adjacent said tuyère construction for holding material to be incinerated, said platform being located above said air ducts to be heated from said heating means to preheat said material.

13. An incinerator having a combustion chamber with grate means for the burning of material thereon, comprising a tuyère construction composed of hollow bars arranged with an end of said bars adjacent to the grate means for the passage of the material from the upper surface of said bars to the grate means, air ducts connected to said hollow bars for conducting air thereto, means associated with said ducts to heat the air passing through the ducts to said bars, and a passage leading from the hollow bars to the grate means for supplying heated air thereto.

14. An incinerator having a combustion chamber with grate means for the burning of material thereon, comprising a tuyère construction composed of hollow bars arranged with an end of said bars adjacent to the grate means for the passage of the material from the upper surface of said bars to the grate means, said bars being inclined upwardly from the rear end of the grate means to be rearwardly of the combustion chamber, a preheating chamber rearwardly of and beneath said bars for the passage of hot gases therein and in contact with said bars, a passage communicating with the combustion chamber and said preheating chamber for conducting hot gases to said preheating chamber, air ducts extending through said preheating chamber and connected to said hollow bars at the upper ends thereof for conducting heated air thereto, and a passage leading from the lower ends of the hollow bars to beneath the grate means for supplying heated air thereto.

15. An incinerator having a combustion chamber with grate means for the burning of material thereon, comprising a tuyère construction composed of hollow bars arranged with an end of said bars adjacent to the grate means for the passage of the material from the upper surface of said bars to the grate means, said bars being inclined upwardly from the rear end of the grate means to be rearwardly of the combustion chamber, a preheating chamber rearwardly of and beneath said bars for the passage of hot gases therein and in contact with said bars, a passage communicating with the combustion chamber and said preheating chamber for conducting hot gases to said preheating chamber, air ducts extending through said preheating chamber and connected to said hollow bars at the upper ends thereof for conducting heated air thereto, and a passage leading from the lower ends of the hollow bars to beneath the grate means for supplying heated air thereto, said latter passage having a portion passing through the combustion chamber above the grate means for receiving heat from the hot gases in the combustion chamber.

16. An incinerator having a combustion chamber with grate means for the burning of material

thereon, comprising a tuyère construction composed of hollow bars arranged with an end of said bars adjacent to the grate means for the passage of the material from the upper surface of said bars to the grate means, said bars being inclined upwardly from the rear end of the grate means to be rearwardly of the combustion chamber, a preheating chamber rearwardly of and beneath said bars for the passage of hot gases therein and in contact with said bars, a platform at the upper ends of said bars for supporting material to be fed down over the upper surfaces of said bars and being located above the preheating chamber for the heating of the material thereon, a passage communicating with the combustion chamber and said preheating chamber for conducting hot gases to said preheating chamber, air ducts extending through said preheating chamber and connected to said hollow bars at the upper ends thereof for conducting heated air thereto, and a passage leading from the lower ends of the hollow bars to beneath the grate means for supplying heated air thereto.

17. In an incinerator having a combustion chamber with grate means for the burning of material thereon; in combination therewith, a preheating chamber adjacent to said combustion chamber and for the passage of hot gases therethrough a tuyère construction between said chambers and forming a common wall portion of said chambers, said tuyère construction having an included wall in said combustion chamber and extending to said grate means for movement of material over said inclined wall to said grate means, an air duct connected to said tuyère construction and located in said preheating chamber for heating of said duct and the air passing therethrough by the hot gases in said preheating chamber.

18. In an incinerator having a combustion chamber with grate means for the burning of material thereon; in combination therewith, a preheating chamber adjacent to said combustion chamber and for the passage of hot gases therethrough, a tuyère construction between said chambers and forming a common wall portion of said chambers, said tuyère construction having an inclined wall in said combustion chamber and extending to said grate means for movement of material over said inclined wall to said grate means, an air duct connected to said tuyère construction and located in said preheating chamber for heating of said duct and the air passing therethrough by the hot gases in said preheating chamber, and a passage communicating with said tuyère construction and leading to said grate means for supplying heated air thereto.

19. In an incinerator having a combustion chamber with grate means for the burning of material thereon; in combination therewith, a preheating chamber adjacent to said combustion chamber and for the passage of hot gases therethrough, a tuyère construction between said chambers and forming a common wall portion of said chambers, said tuyère construction having an inclined wall in said combustion chamber and extending to said grate means for movement of material over said inclined wall to said grate means, an air duct connected to said tuyère construction and located in said preheating chamber for heating of said duct and the air passing therethrough by the hot gases in said preheating chamber, an air chamber communicating with said tuyère construction for receiving heated air therefrom, said air chamber being located adja-

cent said preheating chamber to receive heat from the hot gases therein, and a passage communicating with said air chamber and leading to said grate means for supplying heated air thereto.

20. In an incinerator having a combustion chamber with grate means for the burning of material thereon; in combination therewith, a preheating chamber adjacent to said combustion chamber and for the passage of hot gases therethrough, a tuyère construction between said chambers and forming a common wall portion of said chambers, said tuyère construction having an inclined wall in said combustion chamber and extending to said grate means for movement of material over said inclined wall to said grate means, an air duct connected to said tuyère construction and located in said preheating chamber for heating of said duct and the air passing therethrough by the hot gases in said preheating chamber, and a passage communicating with said tuyère construction and leading to said grate means for supplying heated air thereto, said passage extending adjacent to said grate means for receiving heat from the burning material thereon.

21. In an incinerator having a combustion chamber with grate means for the burning of material thereon; in combination therewith, a preheating chamber adjacent to said combustion chamber and for the passage of hot gases therethrough, a tuyère construction between said chambers and forming a common wall portion of said chambers, said tuyère construction hav-

ing an inclined wall in said combustion chamber and extending to said grate means for movement of material over said inclined wall to said grate means, a platform adjacent to said tuyère construction for holding material to be incinerated, means for feeding said material from said platform to said inclined wall, said preheating chamber being located beneath said platform for heating of said platform by the hot gases in said preheating chamber, an air duct connected to said tuyère construction and located in said preheating chamber for heating of said duct and the air passing therethrough by the hot gases in said preheating chamber.

22. In an incinerator having a combustion chamber with grate means for the burning of material thereon; in combination therewith, a preheating chamber adjacent to said combustion chamber and for the passage of hot gases therethrough, a tuyère construction between said chambers and forming a common wall portion of said chambers, said tuyère construction having an inclined wall in said combustion chamber and extending to said grate means for movement of material over said inclined wall to said grate means, said tuyère construction having an air duct in said preheating chamber for heating of said duct and the air passing therethrough by the hot gases in said preheating chamber, and an air supply conduit extending through said preheating chamber to be heated by the hot gases therein and communicating with said tuyère duct.

RICHARD GODER.
